UNITED STATES PATENT OFFICE.

FRANCIS N. WILLIAMS, OF TAUNTON, MASSACHUSETTS.

LINING FOR FURNACES OR STOVES.

Application filed April 19, 1928. Serial No. 271,324.

This invention relates to a lining for a furnace or stove of any kind for use with natural or artificial gas, or oil for fuel, or even with solid fuel.

5 The principal objects of the invention are to provide a lining adapted to be placed in a stove or furnace constructed for the burning of coal or wood, which will adapt the same for the burning of gaseous or liquid fuel; to provide a lining in such form that the efficiency of the furnace as a gas or oil furnace will be materially increased over that of such furnaces now on the market; to provide for lining a furnace in accordance 15 with this principle, irrespective of the shape, size and use for which the furnace was originally designed; to provide a construction suitable for use in new or old furnaces and stoves to intensify and control the heat 20 produced from the burning fuel by enclosing the burner within a cellular refractory lining at a point near the bottom thereof with sufficient air space above and below the burner to provide for proper combustion; to 25 provide a perforated cover or dome therefor over the side walls of the lining; to provide for regulating the control of the heat developed by the fuel within the lining by the size and number of openings in the drum or 30 cover part; to convert the transmission of heat by convection into radiant heat energy by the presence of the cellular lining; to provide means whereby the heat is adapted to pass through the openings in the side wall 35 of the lining directly to that part of the fire box or combustion chamber exposed thereto; to provide for the transfer to the surface of that part of the combustion chamber or fire box that is in contact with the 40 body part of the cellular lining, all heat possible by conductivity and diffusion and to provide for the escaping of the products of the combustion through the openings in the dome or cover part and the usual flues 45 with which such furnaces are provided.

Other objects and advantages of the invention will appear hereinafter.

Reference is to be had to the accompanying drawings in which

50 Fig. 1 is a view through the center of a certain type of furnace, broken away and partly in section, showing a preferred embodiment of this invention applied thereto, the section line being taken from the front 55 to the back;

Fig. 2 is a plan view of the cover of the

cellular lining removed from the furnace, and

Fig. 3 is a perspective view of one of the blocks of which the lining is formed. 60

The lining which is the subject of this invention can be built into a stove or furnace when constructed and is capable of being introduced into one which already has been constructed for the burning of solid 65 fuel. In either case the furnace wall 10 may be of any desired character and lined in any desired way, as is customary in this industry, or not.

Inside the furnace and with its bottom 70 located about the level of the usual grate, and resting on the grate 11, if desired, I place my improved lining 12, which consists of a series of separate pieces of refractory material, each preferably provided with a 75 number of comparatively large openings 9. These are built up as indicated in the drawings and form the cellular lining, partaking of the shape of the interior of the furnace to which it is applied preferably. Thus the 80 invention is applicable to furnaces of all shapes and sizes including domestic stoves.

The top of the cellular lining is covered by a dome or cover 13 of refractory material, 85 preferably of the same nature as that forming the lining itself and provided with a series of perforations 14 for a purpose to be described. This covers the top of the lining and provides an interior hollow body within the furnace and takes up most of the 90 space in the lower part of the furnace.

At the front a space 15 is shown through which is introduced the fuel supply pipe 16, supplying a burner 17 which is of such size as to provide a sufficient amount of heat. 95 Usually this burner will almost fill the bottom of the lining so as to direct the flames from the burner up the interior surfaces of the lining and enable them to heat the walls of the furnace directly both by convection 100 and radiation through the openings 9 in the lining 12.

It is to be noticed that this lining is of a cellular form, made in sections, preferably, for convenience in production. It is used 105 for the purpose of controlling and intensifying the heat obtained from the burning of natural, artificial or mixed gas or oil within its walls.

The openings 9 in the side walls of the 110 cellular lining can be made of whatever available size may be desired and are for

the purpose of allowing the heat produced from the burning of the fuel to come into direct contact with the inner surface of the fire box or combustion chamber of the stove or furnace that may be exposed thereto through these openings. The openings in the dome 13 are for the purpose of allowing the fumes from the burning gases to escape into the usual flues and to provide 10 the necessary draft. The control of the heat produced in this apparatus is regulated by the number and size of the openings in the dome. It is designed so as to provide the necessary draft and retain as much heat as 15 possible consistent therewith.

The heat transferred by convection heats up the refractory lining and is then transmitted as radiant heat energy for the purpose of heating up the furnace and keeping 20 the heat more even. By providing the refractory lining and its cover to enclose the flame from whatever fuel it is desired to use, the heat radiating in all directions is reflected back against the lining. Thus there 25 is little loss and a very high efficiency is maintained. The lining is heated to any desired temperature by the use of comparatively little fuel, because the radiant heat passes back and forth in all directions and 30 imparts more heat to the refractory lining which again gives it out, partly in the form of radiation back across the furnace and partly as heat conducted through the lining to the furnace wall behind. The combustible 35 gases that, ordinarily, would pass out of the furnace unconsumed are burned in this fire box. This accounts for the high efficiency. After the burner is turned off the latent heat within the refractory material will be available for a considerable 40 length of time. At the same time the in-

terior of the furnace wall is exposed to the direct heat through the openings in the lining so that an intense heat can be obtained by this means in a very short time after 45 the burner is lighted. Yet the advantage of a substantial continuous and uniform heat through the operation of the device is secured.

Although I have illustrated and described only a single form of the invention and shown it as applied only to a single type of furnace I am aware of the fact that the principle can be carried out without departing from the scope of this invention in furnaces of practically all types, shapes and sizes by a corresponding alteration in the size and shape of the cellular lining. 50

Therefore, I do not wish to be limited to any particular type of furnace or shape or 60 size of lining but what I do claim is:—

1. The combination with a stove or furnace, of a cellular lining therein located in the combustion chamber thereof and formed of series of brick of refractory material, each 65 having openings through which heat is supplied to the inside surfaces of the furnace and a fuel burner located near the bottom of said cellular lining.

2. The combination with a stove or furnace, of a cellular lining of refractory material engaging the side walls of the combustion chamber all the way around, a cover over the lining, and a fuel burner located in position to direct its heat into the interior of 70 the lining, whereby the burner is enclosed in the space within the lining and below the cover. 75

In testimony whereof I have hereunto affixed my signature.

FRANCIS N. WILLIAMS.
